United States Patent Office

Des. 213,547
Patented Mar. 18, 1969

213,547

DOOR

Francis Joseph McCabe, P.O. Box 131,
Penns Park, Pa. 18943

Filed May 13, 1968, Ser. No. 11,904

Term of patent 14 years

U.S. Cl. D13—1
Int. Cl. D25—02

Fig. 4

Fig. 1

Fig. 2

Fig. 3

FIG. 1 is a front elevation of the door embodying my new design;

FIG. 2 is a vertical section through an upper portion of the door taken as indicated by the lines and arrows 2—2 in FIG. 1;

FIG. 3 is a vertical section through a lower portion of the door taken as indicated by the lines and arrows 3—3 of FIG. 1; and

FIG. 4 is a horizontal section taken as indicated by the lines and arrows 4—4 in FIG. 1.

The broken lines indicating the structure in which the door is mounted are shown for illustrative purposes only.

I claim:

The ornamental design for a door, as shown and described.
